FOLDABLE ELECTRIC CLOTHES DRIER

Harry Mason, Denver, Colo., assignor, by mesne assignments, to Consolidated General Products, Inc., Houston, Tex., a corporation of Texas

Application May 11, 1953, Serial No. 24,938

Term of patent 14 years

(Cl. D49—2)

To all whom it may concern:

Be it known that I, Harry Mason, a citizen of the United States, residing at Denver, State of Colorado, have invented a new, original, and ornamental Design for Foldable Electric Clothes Drier, of which the following is a specification, reference being had to the accompanying drawing, forming a part hereof.

Fig. 1 is a front perspective view of a foldable electric clothes drier showing my new design.

Fig. 2 is a rear elevational view thereof.

Figure 3 is a perspective view of my new design showing the same folded for storage or transportation, the side shown in elevation being the

top. The bottom which is not shown is identical with the top with the exception that the central hole and the handle have been omitted.

I claim:

The ornamental design for a foldable electric clothes drier, as shown and described.
